UNITED STATES PATENT OFFICE.

JOHN W. JONES, OF SALUBRIA, IDAHO.

DESIGN FOR A BARN-DOOR HINGE.

SPECIFICATION forming part of Design No. 32,032, dated December 26, 1899.

Application filed November 29, 1899. Serial No. 738,735. Term of patent 7 years.

To all whom it may concern:

Be it known that I, JOHN W. JONES, a citizen of the United States, residing at Salubria, in the county of Washington and State of Idaho, have invented and produced a certain new and original Design for Barn-Door Hinges; and I do declare the following to be a full, clear, and exact description of the invention, such as will enable others skilled in the art to which it appertains to make and use the same.

The invention relates to a new and original design for a barn-door hinge; and it consists of a design of the shape and configuration shown in the accompanying drawings, in which—

Figure 1 is a perspective view of a hinge, and Fig. 2 is an end view.

The design comprises a yoke shaped frame 1, consisting of a horizontally-disposed arm 2, ²⁰ connected by a vertical arm 3, both of said arms being provided with rows of apertures 4 and the upper arm having a vertical extension 5, provided with a forked head 6.

What I claim is—

The design for a barn-door hinge, as herein shown and described.

In testimony whereof I have hereunto set my hand in presence of two subscribing witnesses.

JOHN W. JONES.

Witnesses:

EDGAR R. LOBERG,
R. E. WILSON.
